CLAIM

The ornamental design for a single use camera, as shown.

DESCRIPTION

FIG. 1 is a top, front and side perspective view of a single use camera showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is an end elevational view thereof from the left of FIG. 2; and,

FIG. 7 is an end elevational view thereof from the right of FIG. 2.

FIG. 1

FIG. 2

FIG. 3

FIG. 4

FIG. 5

FIG. 6

FIG. 7
